CALVIN D. SMITH, OF BALDWINSVILLE, MASSACHUSETTS.

Letters Patent No. 77,117, dated April 21, 1868.

IMPROVED TILTING CHAIR.

The Schedule referred to in these Letters Patent and making part of the same.

TO ALL PERSONS TO WHOM THESE PRESENTS MAY COME:

Be it known that I, CALVIN D. SMITH, of Baldwinsville, in the county of Worcester, and State of Massachusetts, have invented a new and useful or improved Rocking or Tilting Chair; and I do hereby declare the same to be fully described in the following specification, and represented in the accompanying drawings, of which—

Figure 1 is a side elevation,

Figure 2 a front view, and

Figure 3 a vertical section of it.

From the seat, A, and back, B, of the chair, projections C C extend downward and embrace opposite sides or cheeks of a base-frame, D, which is designed to rest on the floor. Each of the parts C C is connected to the base-frame by means of a journal, d, extended from the frame and into the said part C, the same being to enable the chair to be tilted on such journal.

From the middle of the seat of the chair, a stud, a, projects downward between two vertical arms b b, which, arranged as represented in fig. 3, are hinged to a bar, c, disposed within and extending across the base-frame, longitudinally thereof. Each of these arms is borne against a stop-bar, d', by means of a bow-spring, e, which goes through the two arms, and at its ends is connected with or bears against them, in manner as represented in the drawings.

The stop-bar d' extends across the base-frame just below the stud a.

On tilting the chair, the stud will be alternately carried against the two arms. Each arm, while in motion, will press against and move the spring at one end, the other end of the spring being supported by the other arm. In this way the spring will be caused to operate in either direction to great advantage in checking, as well as facilitating the movements of the chair on or over the base-frame.

I claim as my invention, the combination as well as the arrangement of the stud a, the stop-bar d', the two arms b b, and the spring e, as applied to the chair and its supporting-frame D, and connected together, substantially as specified.

I also claim the arrangement of the stud a, the stop-bar d', the two arms b b, and the spring e, with the chair and its supporting-frame D.

CALVIN D. SMITH.
